UNITED STATES PATENT OFFICE.

FRANK A. MAGEE, OF WENHAM, AND FREDERICK W. OSBORNE, OF BAL-LARDVALE, ASSIGNORS TO THE MAGEE FURNACE COMPANY, OF BOSTON, MASSACHUSETTS.

DESIGN FOR A COOKING STOVE OR RANGE.

SPECIFICATION forming part of Design No. 23,162, dated March 27, 1894.

Application filed July 3, 1893. Serial No. 479,531. Term of patent 14 years.

To all whom it may concern:

Be it known that we, FRANK A. MAGEE, of Wenham, and FREDERICK W. OSBORNE, of Ballardvale, in the county of Essex, State of Massachusetts, citizens of the United States, have invented and produced a new and original Design for Cooking Stoves and Ranges, of which the following is a specification, reference being had to the accompanying drawing in explaining its nature, in which the figure is a perspective view of the range, its lower and upper hot closets and water tank.

The motive of the design is carried into every ornamental plate or part of the range, and it involves the use of acanthus leaf as a foundation or principal feature, although the shape is much modified and changed in the various parts.

As a minor element of the design, a shell-like figure is introduced in various places, principally at the corners of the base and at the center of the box which surrounds the upper flue.

Beginning with the hot closet base, the ornamental features are found in the two doors A, A', and in the end panel A². The doors A, A', are alike. Each has within a rectangular border two curved scroll borders oppositely arranged and forming a panel in which are two acanthus leaf designs, each of which extends from near the center of the panel and separates into branches. The panel also has where the scroll borders come together shell figures, and in each corner of the panel there is an acanthus spray. The same ideas are embraced in the ornamentation of the end plate A², although it is in a somewhat different style. Between the doors A, A', is an acanthus border or pattern arranged to suit a rectangular space, which is lettered a. Each of the doors A, A', has a handle B, comprising a rounded shank or stock b, starting at b' where it is secured to the door, then extended outwardly and downwardly and curving outwardly abruptly at b² to form the handle proper b³, which is somewhat flattened and enlarged. This stock has also the inner curved section b⁴, which extends downward from the upper part of the handle, curved

downwardly inside the section b and is joined with it, and also has extending downward from it the foot b⁵.

The oven door C has a central panel c which receives the name plate D. This panel has 55 the upper and lower curving ribs c', c², and the straight horizontal sections c³ extending from the ends of the curved sections and forming with the straight vertical sections c⁴ the corners of the panel, and the panel also 60 has the curved side sections c⁵. Extending from the corners of this panel border are acanthus leaf figures c⁶, from which run acanthus scrolls filling the intervening spaces, and producing a heavy, rich effect. 65

The name plate D has at each end a conventional circular flower like figure d. Each is surrounded by a wide circular band, from the facing sides of which extend angular bands, the angular bands joining heavy 70 curved bands which form the upper and lower edges of the panels and the ends of which are curved inwardly. In the corners thus formed is a representation of overlapping scale work. Within the curved borders are 75 conventional representations of flowers and involved band scrolls, and they surround a central circular border which may contain any desired figure, and which is represented in the drawing as a thermometer dial and 80 hand. From each side of this circular border extends an ornamental curved figure in two parts, which curve inward toward each other, as they recede from the curved border.

The oven door has a handle C', like that 85 already described. The fire door E has a similarly shaped handle e, and has also a border inclosing the acanthus design e' extending upwardly from the scroll base e². Below the fire door is what may be termed an acan- 90 thus spray e³ formed on the grate plate of the stove, and beginning at the stem or end e⁴, it curves downwardly then upwardly and radiates or separates into diverging sections.

The ash pit door F has a handle f of the 95 pattern of handle already described, and the door itself has outwardly inclined bars extending to a lower border, and the corners of the door are rounded and ornamented with the acanthus leaf pattern. 100

The plate G forming the front of the water tank has a border *g* slightly raised and which receives the ornamental plate *g'*. The lower section of the plate G has a downwardly curved border *g''*, which near its lower end divides or separates into acanthus scrolls *g'''*. The plate *g'* is rectangular in shape and has acanthus leaf scrolls starting from its center *g''*, one having a downwardly, upwardly and inwardly volute curve with an occasional outward branch, and the other being oppositely arranged and curved and of the same type. The edge of the ash pit shelf is wide, as is also the lower band G' and the edge of the top plate and the band G' extends in a curved line beneath the front plate of the water tank.

The range is represented as having the upper hot closet H, and the shelf H'. The shelf H' is in two parts, being separated by the regulator box *h*. This box and the wings *h'* below the shelf H', and the wings *h''* below the upper hot closet are highly ornamented. The wing on each side of the regulator box has an acanthus leaf or spray starting from near the outer upper corner upwardly and then downwardly with diverging branches, and the upper edge of each wing has an S-shaped scroll. The face of the box between the two wings has also two acanthus scrolls which start from very near the bottom at the center and extend horizontally in an outward curve, and separate into two branches, the heavier of which extends downward in a volute form filling the lower corners, and the lighter of which extends upwardly in volute curves with secondary branches forming circular or rounded extensions. The corners of this box are rounded. The wings *h', h''* above the shelf H' together with the box *h''* support the upper hot closet, and upon the box *h''* is an ornamental plate or design, the central part of which is a shell-like or radiating figure surrounded by a wide border in two parts or sections, and below and above the border are acanthus leaves and scrolls. The wings *h''* each have an open work base of bars, which intersect and form diamond shape openings. The outer edge and base of each wing has an urn-like form rising from the level of the lower shelf, then rounded outwardly and then slightly inwardly, then continuing outwardly with a heavy, full curve. The foot shows the acanthus pattern, and it is also found in the border, and continued upon the open work in the form of two branching volute sections. Above the hot closet there is an ornamental back H'', the upper edge of which has outwardly and inwardly curved and straight sections. This top section is ornamented below the border with an acanthus leaf spray which

starts at the top and separates into two long, scroll-like sections.

The hot closet has the doors J, J', and the end plates J'', one of which is shown. These doors J, J', each have rectangular borders forming panels, and in the center of which is a conventional figure J''' of radiating type which is surrounded by scroll borders, which in turn have extended from their ends acanthus leaf patterns, flanked above and below by acanthus scrolls, and a serpentine acanthus spray or figure is arranged upon the hot closet between the two doors, and each door has a handle like the one already described.

Having thus fully described our invention, we claim and desire to secure by Letters Patent of the United States—

1. In a stove or range, the design for an oven door, substantially as herein shown and described.
2. In a stove or range, the design for a fire door, substantially as herein shown and described.
3. In a stove or range, the design for a name plate, substantially as herein shown and described.
4. In a stove or range, the design for an ash pit door, substantially as herein shown and described.
5. In a stove or range, the design for a grate plate, substantially as herein shown and described.
6. In a stove or range, the design for a water-tank plate G and panel *g'*, substantially as herein shown and described.
7. In a stove or range, the design for the lower panel of a flue box and shelf support, substantially as herein shown and described.
8. In a stove or range, the design for the wings *h'* of a shelf support, substantially as herein shown and described.
9. In a stove or range, the design for the wings *h''* of a shelf support, substantially as herein shown and described.
10. In a stove or range, the design for the panel of a pipe box and shelf support, substantially as herein shown and described.
11. In a stove or range, the design for a lower hot closet section, substantially as herein shown and described.
12. In a stove or range, the design for an upper hot closet, substantially as herein shown and described.
13. In a stove or range, the design H'' for a shelf back, substantially as herein shown and described.

FRANK A. MAGEE.

FREDERICK W. OSBORNE.
